UNITED STATES PATENT OFFICE.

WILLIAM C. ANDERSON, OF TOLEDO, OHIO, ASSIGNOR TO THE LIBBEY
GLASS COMPANY, OF SAME PLACE.

DESIGN FOR A GLASS DISH.

SPECIFICATION forming part of Design No. 25,570, dated June 2, 1896.

Application filed March 19, 1896. Serial No. 583,982. Term of patent 7 years.

To all whom it may concern:

Be it known that I, WILLIAM C. ANDERSON, a citizen of the United States, residing at Toledo, in the county of Lucas and State of Ohio, have invented and produced a new and original Design for the Ornamentation of a Glass Dish, of which the following is a specification.

This design relates to the ornamentation of glass dishes, the design generally being applied to the exterior surface of a bowl-shaped dish, such as shown in the drawings.

In the drawings, Figure 1 is a plan view of the complete design; and Fig. 2 is a vertical section through a portion of a bowl-shaped glass dish, to which the design is applied.

The distinguishing features of this design are two quatrefoil figures A and B, one of said figures, A, being larger than the other, said figures inclosing a square-shaped figure C, containing a rosette, which forms the center of the design. The median lines of the larger quatrefoil figure bisect the sides of said square C, and the median lines of the smaller quatrefoil figure pass through said square diagonally from corner to corner, the resultant design as a whole consisting, therefore, of an eight-pointed figure inclosing a rectangular figure.

The lines forming the sides of the larger quatrefoil intersect each other at *a*, near the corners of the inclosed rectangular figure, and on the median lines of the smaller quatrefoil and the lines forming the sides of the smaller quatrefoil B intersect the sides of the larger quatrefoil at *a'* and terminate on the sides of the rectangular figure C at the point of intersection *b* of the median lines of said larger quatrefoil with the sides of said squares.

The above-described intersection of the various lines of the two quatrefoils produces the quadrangular spaces D in the ends of the leaves of said figures, said quadrangular spaces being inclosed by two outwardly and two inwardly curving intersecting lines, each of the spaces of the larger of said two quatrefoils being ornamented by similar four-pointed rosettes, and the spaces E of the smaller figure being ornamented by small diamond-shaped figures.

Opposite each side of the rectangular figure C, forming the center of the design, two triangles *m* are formed, the apexes of which lie in close proximity to the point of intersection of the median line of the larger quatrefoil, said triangles being ornamented by cross-hatching.

From each corner of the central rectangular figure as a center the fan-like figures *n* are formed, having the serrated edges, as shown.

Radiating from the points of the various leaves of the quatrefoil figures to each side of said points are the curved lines *o*, giving to the entire design a gracefully-disposed contour.

What I claim is—

The design for a cut-glass dish substantially as shown.

WILLIAM C. ANDERSON.
